UNITED STATES PATENT OFFICE.

MERLE BUCKER, OF CHICAGO, ILLINOIS, ASSIGNOR TO FRANCIS W. PARKER, JR., OF CHICAGO, ILLINOIS.

CARBURETER.

1,118,917.

Specification of Letters Patent.

Patented Dec. 1, 1914.

Application filed October 26, 1907. Serial No. 399,239.

To all whom it may concern:

Be it known that I, MERLE BUCKER, a citizen of the United States, residing at Chicago, in the county of Cook and State of Illinois, have invented a certain new and useful Improvement in Carbureters, of which the following is a specification.

My invention relates to carbureters and has for its object to provide among other things, means whereby the carbureter may be self adjusting.

The invention is illustrated in the accompanying drawings, wherein—

Figure 1 is a vertical section of a device containing my invention; Fig. 2, a cross section on line 2—2 of Fig. 1; Fig. 3, a perspective of the throttling cylinder; Fig. 4, a perspective of the lower controlling cylinder; Fig. 5, a cross section on line 5—5 of Fig. 1; Fig. 6, a cross section on line 9—9 of Fig. 6.

Like parts are indicated by the same letter in all the figures.

A is the case body which takes the form of a central annular cup or chamber having the cross connection A¹, the annular float A² connected at one side by the bolt A³ with the bar A⁴ pivoted at A⁵ in a lateral projection A⁶ of the central case body. B is a supply valve mounted on the bar A⁴ and passing through a projection B¹ on the case body cover B². This latter is provided with a series of apertures B³ about the valve B, opening at their upper ends into the chamber B⁴. The valve B abuts upon the lower end of the tubular passageway B⁵ which connects with the chamber B⁶ into which leads the supply pipe B⁷. B⁸ is a vent pipe. These several parts constitute the gasoline supply device and the float and valve for controlling the supply of gasoline.

Mounted on the cross connecting pipe A¹ is the needle valve case C with the opening C¹ opposed to the needle valve C² which is screw threaded at C³ and is received into the downwardly projecting pipe C⁴ on the cross connection A¹.

C⁵ is a stuffing box whereby a tight joint is made, and C⁶ is a hand wheel on the lower end of the valve stem C⁷. By operating the hand wheel C⁶ the needle valve can be set in any desired relation to the opening C¹, and since the needle valve case C opens into the connecting pipe A¹ the gasoline will normally stand at the same height about the

needle valve as it stands in the annular gasoline receptacle of the case body A.

On the lower part of the case is an annular flange D into which is screw threaded the casing D¹ into which leads the air supply pipe D². E is a similar smaller annular flange on the bottom of the case body A and into which is screw threaded the lower controlling cylinder which consists of the screw threaded ring E¹ at the top, the bottom E² with the perforations E³ and the internally screw threaded aperture E⁴ and the vertical connecting pieces E⁵, between which are the vertical slots E¹⁰, E¹¹. In the form shown in Fig. 4, there are four of these vertical slots. This lower cylinder is screwed into the desired position and fixed in place by the set screw E⁶.

Returning to the top of the device, we note a central cylindrical part F which forms the inner part of the annular gasoline chamber in the case body A, and projects above the central aperture in the cover B² thereof. It is screw threaded and receives the screw threaded portion F¹ within which is formed a chamber, and into which is screw threaded the discharge pipe F². This part F has vertically projecting portions F³, with intermediate vertical slots F⁴, and, in fact, constitutes the upper controlling cylinder.

The inner throttling cylinder is shaped as shown. The throttle device comprises several elements. It has a downwardly projecting distributing plate G connected to the cylinder proper which is provided with a series of long vertical slots G¹, lateral slots G² in the vertical slot to receive the cross connection A¹, and short vertical slots G³. The cylinder is closed below by a plate G⁴ which is perforated below at G⁵, and has a downwardly projecting reduced cylindrical portion G⁶ associated with a set screw G⁷ whereby it may be secured to the hub G⁸ on the throttling lever G⁹. The plate G⁴ is directed upwardly as shown, and is open at its upper end to inclose the depending cylinder G¹⁰ on the cross connection A¹. This cylindrical portion G¹⁰ connects with the cylindrical portion G¹¹ above the cross connection A¹ so as to make a vertical passageway surrounding the needle valve casing. There is, therefore, a connection from the air supply pipe through the apertures

E³ and G⁵ and about the needle valve casing into the chamber above the needle valve, and thence out through the opening G¹² which always remains between the plate G and the parts associated with it, even when the other connections between the chamber within the casing D¹ and that within the casing F¹ have been closed.

- J is a collar on the cylindrical part G⁶ 10 provided with the controlling handle J¹ and screw threaded at J² to be received into the screw threaded part E⁴. By turning this screw threaded collar, the throttling cylinder and its associated parts may be 15 raised or lowered for the lower controlling cylinder is fixed rigidly in position by the set screw E⁶. When the throttling cylinder has reached the proper position it is locked by the set screw J³. It is, however, 20 free to rotate on its vertical axis. This is accomplished by operating the throttle lever G⁹ which carries with it the cylinder G⁶ and the throttling cylinder and its associated parts.
- 25 This apparatus involves a method or process of producing a mixture suitable for use in internal combustion engines and the feed is responsive to variations in the vacuum in such mixing chamber, such variation in the 30 vacuum being itself responsive to the demands of the engine.

In operation the parts are adjusted as above described and the air inlet and mixture outlet openings set, whereupon a varying 35 vacuum in the mixing chamber will result in such an intake of air and oil as will vary the richness of the mixture to correspond to the necessities of the engine. Preferably when the engine is under a heavy 40 load the intake and discharge ports will be so adjusted that while the total supply of mixture will increase, the richness thereof will be lessened, and as the load decreases the total supply of mixture will be decreased 45 but the richness thereof increased. This result is desirable, because when the throttle is wide open for a high load a larger amount of mixture is admitted to the engine on the intake stroke and therefore the compression 50 is greater and a less rich mixture is needed to make a combustible charge and give the desired amount of power, whereas when the throttle is closed on low load a lesser amount of mixture is admitted to the engine and the 55 compression is therefore less and a richer mixture needed to give a satisfactory combustible charge in the engine. In practice it works out that for high loads the vacuum in the engine usually increases, and since a 60 weaker mixture is satisfactory the carbureter is so adjusted that the vacuum therein decreases, thus feeding less fuel in proportion to the amount of air, whereas for low loads the vacuum in the engine decreases 65 and the vacuum in the carbureter will in-

crease, thus feeding more fuel in proportion to the air.

The use and operation of my invention are as follows: Assuming that the parts are arranged as shown in Fig. 1, and that they 70 have been properly set by fixing the cylinder E³ in position and securing it there by the set screw E⁶, the action of the engine is to draw the mixed fluids out at the top in the direction indicated by the arrows. This, 75 however, means that the air is being drawn into the bottom, as indicated by the arrow, and the gasoline into the gasoline tank and out at the needle valve, as indicated by the arrows. If now, the operator desires to 80 vary the supply of mixed gas to the engine, he may do so by operating the lever G⁹ which will rotate the throttling cylinder, and by rotating it on the other cylinder, will tend to vary the area of the passageway 85 through their respective vertical slots. The vertical slots E¹⁰ in the fixed lower cylinder are those regulated by the vertical slots G⁷ in the throttling cylinder, while in like manner the vertical slots F⁴ are also so regulated: 90 This variation, however, takes place both above and below the needle valve, or in other words, on both sides of the point of gasoline delivery, and this tends to vary the 95 vacuum. Experience shows that where the air is drawn in at a certain pressure, for example below the needle valve, and discharged at a different pressure above, the 100 action of the needle valve touching the supply of gasoline therethrough, does not vary proportionally with the variation in the supply of the air. It is part of my invention, therefore, to control simultaneously and 105 variably the passageways which lead into the chamber about the needle valve and the 110 passageways which lead out of the chamber above the needle valve for the purpose of securing a variable vacuum. By turning the 115 throttle valve handle far enough the vertical slots E¹⁰ and F⁴ may be closed, whereupon a slight supply of air, as previously explained, will pass up through the holes E⁸, E⁵ about the needle valve and into the chamber above it, and thence out above the upper part of the spreading plate G. If the engine works 120 irregularly for any reason so as certainly to require more gasoline while it is working slowly the effect will be as follows: The slowing down of the engine will increase the supply of air and reduce the tendency of the gasoline to flow out of the needle valve and, therefore, the flow of gasoline will tend to increase. The size and relation of these several slots and the positions to which the 125 parts are to be brought for the fixed adjustments, are of course, variable and must be determined for each particular engine and for the conditions under which it is to be operated. My drawings are, therefore, to be taken as diagrammatic and simply as in- 130

tended to illustrate in a general way the application of my invention, but its particular application in any given case would have to be worked out and adjustments would have 5 to be made by some person competent to make such adjustments.

In order to obtain a relative area of outlet and inlet passages for all positions of the throttle and speed of the engine, such that 10 the discharge from the needle valve may insure a proper explosive mixture, one set of ports in Fig. 1 is made independently adjustable by rotating the lower cylinder to any desired position. This may bring the 15 upper and lower slots in the exterior cylinder more or less out of line. Generally speaking, therefore, the device discloses means for initially varying or adjusting the ports, these means being independent of the 20 action of the engine and preferably adapted, and as here shown actually adapted, to vary the effective areas of the ports in opposite directions, thus varying the relative proportions of their areas. These means prefer- 25 ably operate simultaneously and coöperate with the throttling means which, as here illustrated in its preferred form, adjust simultaneously the effective areas of the ports preferably by increments of a uniform ratio. 30 The means for varying the effective areas of the ports in opposite directions, contains the threaded collar J^2 which is adapted to cause the cylinder G^1 to move back and forth in its bearings and thereby to change the area 35 of the ports above and below the liquid reservoir.

I claim:

1. In a carbureter the combination of a liquid discharge valve with an air passage- 40 way into which the same opens, an inlet to the passageway on one side of the valve and an outlet on the other, throttling means for simultaneously varying their effective areas and additional means operative at right 45 angles to said throttling means for adjusting their effective areas.

2. In a carbureter the combination of a liquid discharge valve with an air passage- 50 way into which the same opens, an inlet to the passageway on one side of the valve and an outlet on the other, throttling means for simultaneously varying their effective areas in the same direction, and additional means for simultaneously adjusting their effective 55 areas oppositely.

3. In a carbureter the combination of a liquid discharge valve with an air passage- 60 way into which the same opens, an inlet to

the passageway on one side of the valve and an outlet on the other, throttling means for simultaneously varying their effective areas, and additional means for simultaneously adjusting their effective areas oppositely.

4. In a carbureter the combination of a liquid discharge valve with an air passage- 65 way into which the same opens, an inlet to the passageway on one side of the valve and an outlet on the other, throttling means for simultaneously varying their effective areas in the same direction, and additional means 70 manually operative for adjusting their effective areas oppositely.

5. In a carbureter the combination of a liquid discharge valve with an air passage- 75 way into which the same opens, an inlet to the passageway on one side of the valve and an outlet on the other, throttling means for simultaneously varying their effective areas by increments of uniform ratio, and additional means for simultaneously adjusting 80 their effective areas oppositely.

6. In a carbureter, the combination of a liquid discharge valve with an air passage- 85 way into which the same opens, an inlet to the passageway on one side of the valve and an outlet on the other, throttling means for simultaneously varying their effective areas in the same direction by increments of uniform ratio, and additional means for simultaneously adjusting their effective areas 90 oppositely.

7. In a carbureter the combination of a liquid discharge valve with an air passage- 95 way into which the same opens, an inlet to the passageway on one side of the valve and an outlet on the other, throttling means for simultaneously varying their effective areas by increments of uniform ratio, and additional means for adjusting their effective areas 100 oppositely, said additional means manually operative.

8. In a carbureter the combination of a liquid discharge valve with an air passage- 105 way into which the same opens, an inlet to the passageway on one side of the valve and an outlet on the other, throttling means for simultaneously varying their effective areas in the same direction by increments of uniform ratio, and additional means manually 110 operative for adjusting their effective areas oppositely.

MERLE BUCKER.
